US0D1080878S

(12) **United States Design Patent** (10) **Patent No.:** **US D1,080,878 S**
(45) **Date of Patent:** **** Jun. 24, 2025**

(54) **MOVEMENT ARM**

(71) Applicant: **DENTAL COMPONENTS LLC**,
Newberg, OR (US)

(72) Inventor: **Austin E. Unsworth**, Fort Mill, SC
(US)

(73) Assignee: **DENTAL COMPONENTS LLC**,
Newberg, OR (US)

(**) Term: **15 Years**

(21) Appl. No.: **29/871,591**

(22) Filed: **Feb. 23, 2023**

(51) **LOC (15) Cl.** **24-02**

(52) **U.S. Cl.**

USPC **D24/177**

(58) **Field of Classification Search**

USPC D24/108, 176–182, 107, 133, 152,

(57) **CLAIM**

The ornamental design for a movement arm as shown and described.

DESCRIPTION

FIG. 1 is a perspective view of a movement arm showing the new design;

FIG. 2 is another perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front elevation view thereof; and

FIG. 8 is a rear elevation view thereof.

FIG. 9 is a perspective view of another embodiment of a movement arm showing the new design;

FIG. 10 is another perspective view thereof;

FIG. 11 is a top plan view thereof;

FIG. 12 is a bottom plan view thereof;

FIG. 13 is a left side elevation view thereof, the right side elevation view being a mirror image thereof;

FIG. 14 is a front elevation view thereof; and,

FIG. 15 is a rear elevation view thereof.

The broken lines illustrate portions of the movement arm, and environmental structure of the movement arm, that form no part of the claimed design.

1 Claim, 13 Drawing Sheets
